UNITED STATES PATENT OFFICE.

JOHN A. WALLER, OF HIGHLAND PARK, ILLINOIS.

EXPANDED WOOD LATH.

1,427,246.

Specification of Letters Patent. Patented Aug. 29, 1922.

Application filed November 22, 1919. Serial No. 340,031.

To all whom it may concern:

Be it known that I, JOHN A. WALLER, a citizen of the United States, residing at Highland Park, Cook County, Illinois, have 5 invented certain new and useful Improvements in Expanded Wood Lath, of which the following is a specification.

My present invention is an improvement upon the type of expanded lath shown and 10 described in my Letters Patents Numbers 1314106 and 1314107, and its object is to effect further savings of material, to expedite the manufacture and to make other improvements in this form of lath. With 15 these objects in view my invention consists of the novel construction, combination and arrangement of parts, all as hereinafter described in detail, illustrated in the accompanying drawing and more particularly 20 pointed out in the appended claims.

In the drawing—

Figure 1 is a plan view of a section of expanded lath embodying the present improvements.

25 Figure 2 is an enlarged cross section of Figure 1.

Figure 3 is a similar section showing the parts as they appear prior to the final operation on the expanded board.

30 Figure 4 is a cross section of the blank prior to its expansion.

In the several views 2 represents the entire board expanded into divergent or convergent and connective ribs. In this body 35 2 is formed by special machine designed by me for this purpose a series of cuts or crushed in depressions 3 and 4 running angularly relative to each other and widened to produce spaces and ribs 5 and 6. As 40 shown in Figures 2, 3 and 4 the cuts or depressions 3 and 4 extend only part way through the entire thickness of the board in which they are formed which thickness is indicated at 7 which also represents a 45 connective or major rib which runs parallel to the edges of the board and from which the ribs 5 and 6 diverge or into which they converge as an integral part thereof. The ribs 5, 6 and 7 are rendered separable by 50 making the cuts or depressions in one side of the board and by making in the opposite side of said board a series of parallel cutouts, grooves or channels 8 of sufficient depth to reach the grooves or depressions 55 3 and 4 so that the latter will extend entirely through the thus thinned portion of the

board that are opposite the channels 8. These thinned and alternate full thickness portions prior to expansion are shown in Figure 4. Those portions of the cuts 3 and 4 which end in or are over the full thickness portions 7 are inoperative as separating cuts, whereby the respective ends of the narrower ribs 5 and 6 are held in each adjacent pair of ribs 7, as shown in Figure 1, when the ribs 5 and 6 are spread apart. This spreading of the ribs 5 and 6 at opposite angles from the ribs 7 will cause the expansion of the board 2 as a whole to be effected in a plane substantially at right angles to the plane of the long axis of the board instead of diagonally as when the ribs corresponding to 5 and 6 are substantially parallel to each other. In the latter case the spreading movement will be 75 diagonal to the edges of the board, or cause said edges to move longitudinally in relative opposite directions. This entails a loss of material when the ends of the board 2 are squared after expansion which is obviated in the present improvement, which also makes it possible to expand a board of 80 indefinite width without wastage.

The by expansion separated ribs 5, 6 and 7 are in the present improvement held in 85 their spaced-apart relations by means of ordinary wire laid transversely across the expanded board and formed to provide their own fastening means, or grips, upon the expanded board. Each of these wires 90 —9— is first bent into the wavy form shown in Figure 3 and then by a rapid machine process bent or curved into a series of U-shaped portions 10 which engage three sides of the rib 7 as shown in Figure 2. The 95 U-shaped portions 10 terminate in pinched in humps or lug portions 11 and 12 which are projected toward each other into the fiber of the rib 7, forming therein depressions or recesses 13 and 14 in which the holding portions 11 and 12 are securely held against accidental displacement. This saves the material and labor involved in using separate fasteners such as nails or staples and obviates the liability of such fasteners 105 to become loose in the more or less rough handling that building material is subjected to.

I claim as my invention—

1. A wood lath consisting of a board 110 having therein two series of parallel saw cuts, one series arranged angularly relative

to the other series and joined at their proximate ends by a connective rib, said saw-cuts expanded to form strips of lath, and transverse spacers for holding said strips of lath spaced apart having integral grip portions engaged with portions of said board.

2. An expanded wood lath that consists of a series of strips of lath formed by making a row of parallel and diagonally arranged saw cuts into said board and another similar row extending diagonally in the opposite direction from the first mentioned

row, said saw-cuts extending partly through the thickness of the board from one side thereof, said board having in its opposite side parallel grooves which extend to said saw cuts to form separated strips of lath, and transverse spacers each consisting of a single wire having self contained fastening means engaged with said wood lath. 15 20

In testimony whereof I have hereunto signed my name.

JOHN A. WALLER.
